UNITED STATES PATENT OFFICE.

HARRISON T. WHIPPLE, OF PORTLAND, MAINE.

POCKET MEMORANDUM-BOOK.

SPECIFICATION forming part of Letters Patent No. 308,295, dated November 18, 1884.

Application filed December 3, 1883. (Model.)

To all whom it may concern:

Be it known that I, HARRISON T. WHIPPLE, residing in Portland, in the county of Cumberland and State of Maine, have invented 5 certain new and useful Improvements in Pocket Memorandum-Books; and I do hereby declare that the following is a full, clear, and exact description of the invention, which will enable others skilled in the art to which it applies 10 to make and use the same.

This invention has relation to a new and ingenious improvement in pocket memorandum-books.

The accompanying drawings fully explain 15 my improvement.

Figure 1 is a view with the supplemental flap closed over the memorandum-sheets. Fig. 2 is a view with the flap thrown back. Fig. 3 is an edge view. Fig. 4 is a view of the 20 open case. Fig. 5 is a detail showing the blank book in place inside.

In the several figures of the drawings the same reference-letters are used to designate like parts.

25 In the drawings, *a* represents the case or cover ordinarily used in the construction of pocket letter-cases, covers for detachable account and memorandum books, and the like. This case *a* may be of any desired shape or 30 size and of any suitable material. *b* is a supplemental flap or cover attached at one end to the outside of the case *a* by means of rows of stitches *c c*.

d represents a series of paper sheets attached 35 to the front of the case *a* by means of elastic binding-bands. The series of paper sheets, as shown in the drawings, are so located that the flap *b*, when folded down, completely covers them and protects them from all danger of 40 being torn or blurred or otherwise injured when the device is carried about in the pocket. *e e* are eyelets at or near the top of the case *a*, which are to receive an elastic binding-band, *f*. Other eyelets, *g g*, are seen at 45 or near the bottom of the case *a*. Through these eyelets pass binding-bands *h h*. The binding-bands *f* and *h h* are to hold and confine the series of paper sheets *d* firmly and securely in position. In attaching the sheets *d*

to the outside of the case *a* the sheets are 50 confined at the top by the band *f*, running from side to side, while at the bottom the sheets are held by the bands *h h*, running across the corners. This method of binding the paper sheets is of considerable importance. By it 55 the sheets can be readily attached or detached, and the cross-bands *h h* prevent the sheets from slipping downward, and also prevent the corners of the sheets from becoming dog-eared. 60

Opening the case *a*, the small detachable blank book *k* is seen attached to the case at the folding-line by means of a binding-band, *m*, said binding-band passing through eyelets *o*. This method of attaching a blank book to 65 a pocket-case is too well known to require further description.

p p represent slips or pockets on the inside of the case *a*.

The use and application of the device is obvious and does not call for elaboration. As a handy pocket device for recording memoranda of events, &c., which are of so transitory a character that a person does not care to make a permanent record of them, my invention 70 presents many very decided advantages, a few of which are as follows: The sheets are easily attachable and removable. The binding-bands hold the sheets securely in position. The flap obviates all danger that anything 75 written upon a memorandum-sheet will be defaced or destroyed by carrying in the pocket.

What I claim as my invention, and desire to secure by Letters Patent, is—

1. A pocket letter-case, detachable account-book case, or other analogous device, to one cover of which is stitched a supplemental flap or protector, substantially as described, said flap or protector covering and protecting a series of paper sheets, which are attached 85 to the case-cover by means of elastic binding-bands, located as herein set forth, substantially as and for the purposes specified.

2. In combination with the case *a*, having eyelets *e e* and *g g*, the binding-bands *f* and *h h*, for holding a series of paper sheets, *d*, in position, the stitched flap or protector *b*, for covering said paper sheets *d*, all the parts co-op- 90 95

erating substantially as and for the purposes set forth.

3. A pocket-memorandum, account-book, and letter-case consisting of the following 5 parts in combination: the case *a*, supplemental flap *b*, eyelets *e e* and *g g*, binding-bands *f, h h*, and *m*, and detachable blank book *k*, operated and combined substantially as set forth, for the purposes specified.

In testimony that I claim the foregoing as my to own I have affixed my signature in the presence of two witnesses.

HARRISON T. WHIPPLE.
